UNITED STATES PATENT OFFICE

ARMAND GODEFROID, OF BERLIN, GERMANY

COIN-ASSORTING APPARATUS

Application filed June 28, 1928, Serial No. 238,822, and in Germany December 30, 1925.

This invention relates to a device for assorting mixed coins and its object is to produce a compact apparatus the essential parts of which are of simple construction and reliable and speedy in operation, and the invention consists in the first place in arranging a plurality of sorting channels in a longitudinal position relative to the drawer or other coin receptacle and in a plurality of tiers so as to maintain the surface extent and height of the apparatus within small limits and expedite the sorting operation.

In order to distribute the coins among the different sorting channels, a hopper is provided which has several compartments and which is capable of turning the coins from a horizontal into a vertical position before they are delivered into the channels.

For the distribution of coins between the channels of the same tier, the upper channel or channels are formed with coin supports which are narrower than the thinnest coin so as to prevent two coins from running abreast along the same channel. By this arrangement the additional advantage is obtained that the frictional resistance offered to the coins will be reduced so that the coins will pass through the sorting device at a greater speed.

In the accompanying drawings the invention is illustrated in conjunction with a cash register.

Fig. 1 representing a longitudinal section of the register,

Fig. 2 a vertical section of the same taken on the line 2—2 of Fig. 1,

Fig. 3 a side view of the sorting channels,

Fig. 4 a top view of the same in section on the line 4—4 of Fig. 3, and

Fig. 5 a cross-section on the line 5—5 of Fig. 3.

The cash register is provided with a cash tray 1 which is mounted on pivots 2 between the side walls 3 of the register and is adapted to be tilted about the pivots for discharging the received coins on to an endless apron 4 supported on rollers 5 and 6. The apron is covered by a glass plate 7 which allows the amount to be checked on the apron in case of dispute. The apron delivers the mixed coins

into a hopper α which is divided, transversely of the apron, into several compartments formed of curved plates 9 and 10. The plates of adjacent compartments converge so as to form a roof over which the coins are separated and righted, and a gutter 12 is produced between each pair of adjacent roofs wherein the coins are received in an upright position. Wires 11, strung centrally across the hopper compartments, assist in distributing the coins over the different compartments.

The coins are delivered by the hopper into sorting channels β which are situated under the apron 4 and arranged in tiers of two or more channels, there being one tier for each gutter 12. The channels are inclined in the direction of their length and also sideways so as to cause the coins to bear against and to be guided by one side only of each particular channel. In the present instance, where there are two channels in each row, there is a bar 15 which forms the top support for the coins in the upper channel. Another bar 16 forms the bottom support β^1 of the upper channel and at the same time the top support of the lower channel. The bottom support β^2 of the lower channel is formed with a plate 17 which may be integral with a plate 14 which covers, entirely or partly, the off-sides of both channels.

The bottom support β^1 of the upper channel is composed of a list 18 formed on the bar 16. This list, which is flush with the gutter 12 is narrower than the thinnest coin so that, if two coins should be received together by the gutter, only one of them will be retained on the list, the other being dropped into the lower channel. Those portions 15' and 16' of the bars 15 and 16 against which the top edges of the coins rest, are stepped off, as shown in Fig. 3, so as to form between them and the lower support, graded apertures 18 through which the tilted coins may fall out of the channels sooner or later according to size. Cross-walls 19 extending from tier to tier at each change in the discharge aperture, keep the assorted coins separate and guide them into chutes σ whereby they are delivered into separate compartments 20 of a

drawer or other coin receptacle arranged, like the channels, in the longitudinal direction of the apparatus so as to reduce the surface extent of the latter.

- 5 The surfaces of the bars 15 and 16 against which the coins of the underlying channels rest, are beveled off as shown at *x* in Fig. 5 so as to support the coins at the extreme top edge only. By this arrangement and by the 10 provision of the narrow supporting list 13, the frictional resistance offered to the coins will be very low, and the coins will travel correspondingly fast down the channels. The inclination of the latter can therefore be 15 moderate, and the outer portions of the channels can, as shown in Fig. 1, be horizontal or even upwardly inclined so as to reduce the height of the apparatus.

In order to brake the velocity of the coins 20 at the moment of delivery and prevent overthrow, the top supports may be straightened out as shown at *y* in Fig. 5 at the delivery points so as to contact with the greater portion of the coins.

25 By arranging the sorting channels in a plurality of tiers as described, a rapid action of the apparatus is ensured.

The device hereinbefore described may be combined with any type of cash register.

30 I claim:

1. In an apparatus for sorting coins wherein a plurality of sorting channels are carried in tiers above distributing hoppers and coin receptacles and wherein the said sorting 35 channels are inclined towards one side and have graded apertures for the discharge of coins; the improvement which comprises a coin sorting channel having the upper bearing surface for said coins beveled so as to 40 contact only with the top edge of said coins, whereby the friction of said coins against the side of said sorting channel is reduced.

2. A coin sorting apparatus having the 45 structure of claim 1 wherein the beveled bearing surface for said coins is formed on a bar the upper edge of which forms a bottom support for coins passing through an upper sorting channel.
